A. W. UHL
APPARATUS FOR DETECTING THE PRESENCE
OF SUSPENDED MATTER IN FLUIDS
Filed Nov. 30, 1949

INVENTOR.
ARTHUR W. UHL
BY

J. William Carson
ATTORNEY

smoke and air is prevented from entering the casing.

A photoelectric cell 40 is mounted in a casing 42 at the end of the smoke or detector tube 26 opposite the light source and in the direct path of rays of light from the detector lamp 34.

The detector tube 26 has a plurality of inlet openings 46 in the wall thereof adjacent the inner end of the casing 36, and an outlet opening 48 is provided adjacent the other end of the detector tube. The outlet 48 communicates with an exhaust conduit 50 in which a motor driven blower 52 or other suction device is mounted for drawing air or smoke from the protected space or area through the inlet 18 in the housing 10, or through the filter tube 20, past the spacer members 28, through the openings 46, into the detector tube 26 and hence into the path of the light rays from the detector lamp 34, and out of the opening 48 through the exhaust conduit to the atmosphere. The air drawn into the detector tube 26, in passing between the spacer members 28, tends to retain the detector lamp and its casing cool.

The electric conductors for the detector lamp and the photoelectric cell are enclosed in a conduit 54, the opposite ends of which are connected to and supported by junction boxes 56 and 58 which are mounted respectively on the housing 10 and the detector tube 26.

Any conventional relay for operating an alarm circuit may be connected into the photoelectric cell circuit and employed with the apparatus of the present invention, hence it is not necessary to illustrate and describe such relay and alarm circuit.

When it is desired to remove the light source or detector lamp for replacement, or to remove the lens or filter means for cleaning, it is merely necessary to loosen the screws 16, withdraw the section 12 from the section 14, then remove the casing 36, replace the light bulb through the opening 37, clean the lens, and again insert the casing in place. When the section 12 has been removed it is a simple operation to merely withdraw the filter tube or screen 20 from the section 12, whereby the same may be cleaned.

While the casing 36 is frictionally held in the end of the smoke tube 26, means may be provided to retain the casing in place in the event the frictional engagement between the casing and the inner wall of the tube 26 is insufficient to retain the casing in place under all conditions of use of the apparatus. The means provided for the said purpose comprises a U-shaped spring member 60, one end of which is secured to the collar 22 of the filter tube by a screw 62, and the other end of which is in engagement with a projection 64 on the base of the socket for detector lamp 34. As will be seen from Figure 1, upon removal of the filter tube, in the manner previously described, the spring member 60 will be removed therewith permitting the removal of the casing.

Insofar as the novel features of the present invention are concerned, the apparatus may be employed as a visual detector for suspended matter in fluids, by having the detector tube 26 made of transparent material, such as glass, plastic or the like, or by providing a transparent window in the tube 26, whereby when no suspended matter is present in the air in the tube, or being drawn therethrough, the light rays will not be visible but when suspended matter is present the

same will be illuminated by the rays of light and be readily visible.

From the foregoing it will be seen that the present invention provides a novel smoke detecting apparatus, wherein the light source is completely sealed in a casing to prevent dust or dirt contacting the light bulb, and wherein the parts are readily removable for cleaning or replacement.

While I have illustrated and described a preferred embodiment of my invention, it is to be understood that I do not wish to be limited to that precise structure, as obviously various changes and modifications may be made therein without departing from the spirit and scope of my invention.

I claim:

1. Apparatus for detecting the presence of suspended matter in fluids comprising an elongate cylindrical tube having a fluid inlet opening in its side wall adjacently spaced from one end and having a fluid outlet opening adjacent its other end, a sealed casing removably positioned in said tube between said inlet opening and the adjacent end of the tube including a light source, a lens forming a closure between said light source and said inlet opening and a closure for said last mentioned end of said tube, a housing section surrounding said tube in coaxially spaced relation thereto to provide a passage and extending inwardly from said last mentioned end of said tube to beyond said inlet opening, closure means between said tube and the inner end of said housing section, a second housing section extending outwardly from said last mentioned end of said tube and having a central opening at its outer end, means for removably securing the outer end of said first housing section and the inner end of said second housing section, a generally tubular screen positioned in said second housing section having its wall adjacent the interior of said second housing section at its inner end and having its wall converging towards the outer end of said second housing section and adjacent spaced from said opening therein, and an element on the converging end of said screen facing said second housing section opening.

2. Apparatus for detecting the presence of suspended matter in fluids comprising an elongate tubular member having a fluid inlet opening in its side wall adjacently spaced from one end and having a fluid outlet opening adjacent its other end, a housing section surrounding said member in coaxially spaced relation thereto and extending inwardly from said first mentioned end of the member to beyond said inlet opening, said section having a fluid entrance at its outer end, an electric lamp, and a tubular casing for said lamp having imperforate end walls and having a side wall formed with an opening in sealing engagement with the inner wall of said member to close said opening to prevent fluid from contacting the latter, said casing being removably positioned in said member between said inlet opening and the adjacent end of the member, the space between said housing section and the member providing a fluid flow passage from the fluid entrance to the fluid inlet opening in said member-by-passing said sealed casing.

3. Apparatus for detecting the presence of suspended matter in fluids comprising an elongate tubular member having a fluid inlet opening in its side wall adjacently spaced from one end and having a fluid outlet opening adjacent its other end, a housing section surrounding said mem-

ber in coaxially spaced relation thereto and extending inwardly from said first mentioned end of the member to beyond said inlet opening, a tubular extension removably secured to the outer end of said section and having a fluid entrance at its outer end, a light source, and a casing for said light source to prevent fluid from contacting the latter having an opening in the wall thereof and having imperforate end walls, said casing being removably positioned in said member between said inlet opening and the adjacent end of the member and rendered accessible upon the removal of said extension, the wall of said member cooperating with the casing to effectively close said opening when the casing is so positioned, and the space between said housing section and the member providing a fluid flow passage from the fluid entrance to the fluid inlet opening in said member by-passing said sealed casing.

4. Apparatus for detecting the presence of suspended matter in fluids comprising an elongate tubular member having a fluid inlet opening in its side wall adjacently spaced from one end and having a fluid outlet opening adjacent its other end, a housing section surrounding said member in coaxially spaced relation thereto and extending inwardly from said first mentioned end of the member to beyond said inlet opening, said section having a fluid entrance at its outer end,

a light source, a casing for said light source removably positioned in said member between said inlet opening and the adjacent end of the member, said casing having an opening in the wall thereof to provide access to the light source when the casing is removed from the member, the wall of the member cooperating with the casing to effectively close said opening when the casing is in place, whereby to prevent fluid from contacting said light source, the space between said housing section and the member providing a fluid flow passage from the fluid entrance to the fluid inlet opening in said member by-passing said sealed casing.
